UNITED STATES PATENT OFFICE

FRANK J. NOLAN, OF NEW YORK, N. Y., ASSIGNOR TO THERMO INDUSTRIES, INC., OF NEW YORK, N. Y., A CORPORATION OF NEW YORK

OIL-GAS MAKING

Application filed April 28, 1927. Serial No. 187,366.

This invention relates to oil gas making and is herein disclosed as applied to the production of a gas from oil and water which has a high calorific value.

5 According to the present invention it has been found possible to produce a gas from heavy petroleum oil without residue and with the apparent absorption of a large part of the heat used in its production, so that the 10 heat was not lost but reappeared in the flame of the burning gas when used.

To effect this result measured quantities of oil and water are fed into a relatively short hot tube with the continuous production of 15 the desired gas. To utilize the gasifying heat to the best advantage and to prevent a relatively cool core of gas or vapor from forming, the tube may be closed at one end, say 20 the base, and the oil and water fed into the closed base by a central tube open at its end. Thus the entering oil and water are heated, and apparently vaporized, in the center of the gasifying tube.

It is found that the stack gases may have a 25 temperature not exceeding 700° F. and that the effluent gas from the tube may have a temperature not exceeding 600° F., and sometimes much lower, thus indicating a great absorption of heat in the gasifying 30 operation.

It has been found that a generator may contain a number of such gas generating tubes, thus enabling a single flame to heat all the tubes. The effluent gas may be conveyed, often substantially without cooling, 35 to a compressor and compressed either as gas or to a liquid into tanks or metal bottles. Alternatively it may be stored in a holder or gasometer.

40 The gas may be produced so as to burn with a brilliant white flame, indicating the presence of a large proportion of unsaturated hydrocarbon compounds, and such a gas may be produced while so operating the process 45 that there is no production of tar or other material which is liquid at ordinary temperatures.

The gas produced has been found fully as effective as acetylene for metal welding and 50 cutting, and may be stored at low or high

pressures for weeks even in cold weather without precipitating any liquid.

Other features and advantages will hereinafter appear.

In the accompanying drawings:

55 Figure 1 is a side view with parts in section of a generator with much of the wall and some other parts broken away.

Figure 2 is a side view partially broken away, on a larger scale, of a forced feed unit.

60 Figure 3 is a plan view of a plant for producing and collecting gas.

Figure 4 is an enlarged detail showing the mixing chamber in elevation with the parts in vertical section.

65 Figure 5 is a diagrammatic side view of a cooler.

Oil is fed to an oil gas generating retort unit 1 by a device adapted to feed measured amounts, herein shown as a force feed pump 2 driven by a suitable motor 3. The oil is delivered through a pipe connected by a double union 5 to an internal delivery pipe 6 lying within the unit 1. Water which may be preheated by flowing through a coil in 75 the stack described below, is simultaneously delivered, also in measured amounts, as by a force pump 7 through a pipe 8 connected to the union 5 so that predetermined amounts of oil and water flow down through the pipe 80 6 into the unit 1. Thus the water and oil are protected from the direct heat exchange with the hot products of combustion from the heating burner by gas rising in the unit 1 around the outside of the pipe 6 except for a short distance between the header and the furnace where a direct application of heat is applied.

85 The unit 1 is one of several, descending from a header 9 in the upper part of a circular housing or furnace 10. The units are heated by an oil burner 11. When suitable proportions of oil and water flow into a hot unit, they are transformed completely 90 into a gas. The heated vapors and gases rise around the pipe 6, which is held centrally in the unit by a spider 12 screwed to the lower end of the pipe 6 and having projecting arms 13. These arms serve as baffles 95 to mix the gas or vapor rising between them, 100

and thus prevent a cool core of gas from forming remote from the hot outer wall of the unit 1.

The hot vapors or gas rise around the pipe 6 in the unit 1, entering the manifold 14 of the header 9 by which time the vapors have been transformed into fixed oil gas, and the gas flows through a six inch off-take 15 twelve feet long going through a boiler-like 10 tubular water-cooled cooler 17, if found advisable.

The gas may go through a meter 16 to a suitable compressor 18, where it may be compressed as a gas or to a liquid, being delivered by a pipe 19 to tanks or metal bottles, not shown, or it may go to a gasometer 20.

The units 1, of which four are shown have been found satisfactory when six feet long and two inches in internal diameter, of half- 20 inch cast heat resistant alloy, with a closed rounded end. The pipes 6 have been found satisfactory when made of three-quarter inch extra heavy wrought iron pipe extending down within the units 1 to within six inches 25 of their bottoms. The lower six inches in each unit 1 form a gas mixing space providing for the first expansion and mixing of gas and vapors.

The header 9 has been found satisfactory 30 when made of the same metal as the units 1, and is provided with internally chamfered flanges 21 into which fit beveled collars 22 on the tops of the units 1, the fit being fairly close and the units being held in place by 35 slightly caulking down the metal on the header. Since there is substantially no pressure in the units 1, threading them is unnecessary.

The header manifold 14 has been found 40 satisfactory when a foot deep. The header 9 is shown as supported by projecting arms 23 which are held by bolts and rest on the walls of the fireproof housing 10. The top 24 of the header is provided with a flange 45 25 by which it is bolted to a projecting flange 26 of the header. The pipes 6 are threaded where they pass through the top 24 and are provided with flanges 27 screwed on at these 50 points, one flange above and one below the top 24, thus firmly supporting the pipes 6 at any adjusted height within the units 1.

The oil burners 11 of a conventional type have been found to work satisfactorily when entering the housing horizontally and tangentially a foot or more below the lower 55 ends of the units 1, in a housing five feet six inches inside diameter and about ten feet high.

The products of combustion leave by a 60 stack 28, twelve inches in diameter provided with an asbestos rimmed damper 29 by which it may be substantially closed or partly closed at will, thus enabling the flame to be directed nearly circumferentially around the 65 oil gas generating retorts.

In one run the burner was operated an hour until the temperature on a pyrometer two feet within the housing about a foot above the burner and on the side away from the flame showed 1800° F. Then an oil composed of one half 28/32 degrees Bé. gas oil and one half 36/42 degrees Bé. gas oil was fed without pressure through sight feed devices at the rate of 100 drops a minute to each unit 1. At the same time water was fed at the rate of 38 drops a minute to each unit by other sight feed devices. The temperature rose during the run in an hour to 1900° F. at the same point. The damper having been nearly closed after the housing was heated up. The gas was a "dynamite smoke" yellow in color, this being the gas best adapted for iron and steel cutting. 75 80

In other runs it was found that the quality of the gas could be varied, a larger proportion of oil producing a darker gas. The gas was run through the cooler which was 59 by 36 inches, but no water was present around the tubes of the cooler. In the course of the run the temperature of the cooler 85 90 rose from 74 at the beginning to 82° F. at the end of the hour. No liquid or solid condensed out of the gas anywhere in the system.

At the end of the run, after the oil burner had been shut off the temperature within the housing at the same point was 1400° F. Higher up, near the bottom of the header, at this time, the temperature was 1370° F. 95

By varying the proportions gas could be 100 obtained with either a water or an oil condensate which separated out on cooling. In one other run, four and one-half gallons of water were fed with six and one-half gallons of oil, and half a gallon of water was condensed out. The units 1 never clogged with tar or coke. 105

Gas from one run showed the following analysis:

	Per cent by volume	110
Carbon dioxide	2.03	
Ethylene	24.95	
Carbon monoxide	4.26	
Methane	33.66	
Hydrogen	31.53	115
Oxygen	1.42	
Nitrogen	2.15	

B. t. u. per cu. ft., 900.5.

Such gas used at five pounds pressure in a burner of a well known make with oxygen at forty pounds cut through a 4 3/4 inch iron shaft in 82 seconds. The same gas with oxygen at twenty pounds cut through a 3 inch bar of 5/8 inch iron in 18 seconds. It was 120 also successfully used in other torches, as in welding together bolt heads. It was found possible to weld cast iron or steel by this gas without case-hardening the iron or steel. The gas at three pounds pressure ran a four 125 130

cylinder combustion engine of a well known make very efficiently. At a half pound pressure per square inch the gas burned with a very brilliant white light, and it burned well in a domestic gas cooking stove, both with and without the usual admixture of air. If desired there may be provided check valves 5, 30, 31 for the oil and water pipes above the double unions 5.

Having thus described certain embodiments of my invention what I claim is:

1. In an oil gas generating apparatus, a closed furnace having a refractory lining, a header entirely within said furnace having an oil gasifying tube depending therefrom, said header including a gas collecting means, said tube being closed at its lower end and open to the interior of said header at its upper end, a second tube of smaller diameter than said first-named tube connected to a source of oil and water supply and extending thru said header and terminating at a point substantially above the closed end of said first-named tube, means for heating said tube, and means for conducting the gas collected in said header from said furnace.

2. In an oil gas generating apparatus, in combination, a closed furnace having a refractory lining, a header within said furnace near the top thereof, a plurality of tubes depending from said header, each of said tubes being closed at their lower ends and open to the interior of said header at their upper ends, a plurality of smaller tubes connected to a source of oil and water supply extending into said furnace and thru said header, one of said smaller tubes extending into each of said first-named tubes and terminating in the region of the closed ends thereof, a burner located in the side of said furnace projecting a flame against the lower ends of said first-named tubes, and a conduit for conducting the gases generated in said first-named tubes from said header to a point exteriorly of said furnace.

3. In an oil gas generating apparatus, a header having an oil gasifying tube depending therefrom, said tube being closed at its lower end and open to the interior of said header at its upper end, a smaller tube leading from a source of oil and water supply extending thru said header and interiorly of said oil gasifying tube and terminating in the vicinity of the lower end of said oil gasifying tube, means for heating said first-named tube, and means for heating said smaller tube prior to its entry into said header whereby vaporization of the oil and water in said line occurs within said smaller tube.

4. In an oil gas generating apparatus, a header having a plurality of tubes depending therefrom, each of said tubes being closed at its lower end and open to the interior of said header at its upper end, a plurality of smaller tubes connected to a source of oil

and water supply and extending thru said header, one of said smaller tubes extending well down into each of said first-named tubes and terminating near the closed end thereof, and a burner directing a flame across the lower ends of said first-named tubes, said smaller tubes being exposed to the heat from said flame prior to their entry into said header.

5. In an oil gas generating apparatus, a header, a plurality of oil gasifying tubes depending from said header, each of said tubes being closed at its lower end and open to the interior of said header at its upper end, a plurality of smaller tubes connected to a source of oil and water pressure supply extending thru said header, one of said tubes terminating near the closed end of each of said first-named tubes, a burner directing a flame across the lower ends of said first-named tubes, and means for directing a portion of the excess heat from said burners against said second-named tubes prior to their entry into said header.

6. In an oil gas generating apparatus, a header, an oil gasifying tube depending from said header, said tube being closed at its lower end and open to the interior of said header at its upper end, a furnace enclosing said header and said tube and having an oil and water line extending thru the top thereof, thru said header and into said tube, said oil and water line terminating at a point in the vicinity of the closed end of said tube, means for maintaining said water and oil line in substantially coaxial relation with said tube, and a burner located in the side of said furnace directing a flame against the bottom of said tube, said furnace directing a portion of the heat rising from said burner to that portion of the oil and water line between the top of said furnace and said header.

7. In an oil gas generating apparatus, a header, a tubular member depending from said header, said member being closed at one end and open at the other end to the interior of said header, a smaller tube extending from a point outwardly of said header through said header and longitudinally within said tubular member and terminating near the bottom thereof, means for applying direct heat to said smaller tube prior to the entry thereof into said header whereby the oil and water therein is subjected to a sudden rise of temperature, means for applying direct heating to said tubular member at the bottom thereof, whereby said tubular member is subjected to an indirect heating, pressure means supplying oil and gas to said tube, said last named means forcing the vapor and gas against the heated bottom of said tubular member to complete the gasification thereof, and means for collecting the gas from said tubular member.

8. In an oil gas generating apparatus, a

- closed furnace having a tubular member closed at its lower end suspended therein, a water and oil line extending thru the top of said furnace and extending longitudinally within said tubular member, said line terminating near the closed end of said tubular member, means for applying direct heating to said tubular member at the closed end thereof, means for heating said line prior to its entry into said tubular member whereby vaporization and gasification of the water and oil occurs within said line, means for exerting pressure on said water and oil to force the vapor and gas formed in said line against the bottom of said tubular member whereby the gasification thereof is completed, and means for collecting the gas from said tubular member exteriorly of said furnace.
9. In an oil gas generating apparatus, a closed furnace having a closed tubular member suspended therein, a water and oil line extending thru the top of said furnace and into said tubular member, said line terminating near the closed end of said tubular member, a burner located in said furnace directing a flame against said tubular member, said line being exposed to the direct heat of the products of combustion from said flame between its point of entry thru said furnace and its point of entry into said tubular member whereby vaporization and some gasification of the water and oil occurs within said line, pressure means forcing said vapor and gas out of said line and against the said tubular member to complete the gasification thereof, and means for conducting the gas from said tubular member exteriorly of said furnace.
10. In an oil gas generating apparatus, a closed furnace having a closed tubular member suspended therein, an oil and water line projecting into said furnace and extending longitudinally of said tubular member, said line terminating in the vicinity of the lower end of said tubular member, means for maintaining said line in substantially coaxial relation with said tubular member, a burner supported in the side of said furnace directing a flame at the lower end of said tubular member, said oil and water line receiving direct heating by the products of combustion from said flame between its point of entry into said furnace and its point of entry into said tubular member whereby vaporization and some gasification of the oil and water occurs within said line, pressure means forcing the vapor and gas from said line into said tubular member, baffle means comprising the arms of the means maintaining said line and said tubular member coaxial, causing the tumbling of the vapor and gas against the sides of said tubular member to complete the gasification thereof, and conduit means for conducting the gases from said tubular member exteriorly of said furnace.
11. In an oil gas generating apparatus, a closed furnace having a closed tubular member suspended therein, an oil and water line projecting into said furnace and extending longitudinally of said tubular member, said line terminating in the vicinity of the lower end of said tubular member, means for maintaining said line in substantially coaxial relation with said tubular member, a burner supported in the side of said furnace directing a flame at the lower end of said tubular member, said oil and water line receiving direct heating by the products of combustion from said flame between its point of entry into said furnace and its point of entry into said tubular member whereby vaporization and some gasification of the oil and water occurs within said line, pressure means forcing the vapor and gas from said line into said tubular member, and conduit means leading from said tubular member exteriorly of said furnace.
12. In an oil gas generating apparatus, a closed furnace having a closed tubular member suspended therein, an oil and water line projecting into said furnace and extending longitudinally of said tubular member, said line terminating in the vicinity of the lower end of said tubular member, means for maintaining said line in substantially coaxial relation with said tubular member, a burner supported in the side of said furnace directing a flame at the lower end of said tubular member, said oil and water line receiving direct heating by the products of combustion from said flame between its point of entry into said furnace and its point of entry into said tubular member whereby vaporization and some gasification of the oil and water occurs within said line, pressure means forcing the vapor and gas from said line into said tubular member, baffle means in said tubular member causing the tumbling of the vapor and gas therein against the sides thereof to complete the gasification thereof, and conduit means for conducting the gas in said tubular member exteriorly of said furnace.
13. In an oil gas generating apparatus, a closed furnace having a furnace lining, a header suspended in said receptacle and having a header and indirect heating thruout its lengthing a plurality of tubular members depending therefrom, each of said tubular members being closed at its lower end and open to the interior of said header at its upper end, a burner projecting a flame interiorly of said furnace in the region of the lower ends of said tubular members, a plurality of water and oil lines extending thru the top of said furnace and thru said header, one of said lines extending into each of said tubular members and terminating near the bottom thereof, each of said oil and water lines traversing a portion of the furnace prior to entry into said header whereby it receives

a direct heating by the products of combustion from said flame prior to entry into said header and indirect heating throughout its length interiorly of said header and its respective tubular member, thereby causing vaporization and a certain amount of gasification of the oil and water in said line, pressure means forcing the vapor and gas from said lines and against said tubular members to complete the gasification thereof, and means for conducting the gas from said tubular members and said header to a desired point exteriorly of said furnace.

Signed at New York, in the county of New York and State of New York, this 27th day of April, A. D. 1927.

FRANK J. NOLAN.
